(57) **CLAIM**

The ornamental design for a mini toilet brush, as shown and described.

DESCRIPTION

FIG. 1 is a front perspective view of a mini toilet brush which embodies the design;

FIG. 2 is a front view thereof; the rear view thereof being a mirror image of the front view thereof

FIG. 3 is a right side view thereof; the left side view thereof being a mirror image of the right side view thereof;

FIG. 4 is a top view thereof; and,

FIG. 5 is a bottom view thereof.

The broken lines shown in the drawings are for the purpose of illustrating unclaimed portion of the mini toilet brush and -forms no part of the claimed design.
